UNITED STATES PATENT OFFICE.

JOHN BARNHART, OF ALTOONA, PENNSYLVANIA.

STEAM-BOILER.

SPECIFICATION forming part of Letters Patent No. 412,718, dated October 15, 1889.

Application filed June 8, 1889. Serial No. 313,542. (No model.)

To all whom it may concern:

Be it known that I, JOHN BARNHART, a citizen of the United States of America, residing at Altoona, in the county of Blair and State of Pennsylvania, have invented certain new and useful Improvements in Steam-Boilers, of which the following is a specification, reference being had therein to the accompanying drawing.

10 In vertical steam-boilers which are constructed with flues extending above the water-line and connected at their upper ends with an upper flue-sheet an objection exists by reason of the liability of the flues to become loosened at their connection with the said flue-sheet, thus rendering leakage of steam possible and impairing greatly the use of the boiler. This objection arises by reason of the fact that the upper ends of said flues being 15 above the water-line are not subjected to the modifying influence of said water, and thus when the fire is started the heat causes them to expand quickly at their connection with the flue-sheet, and as said sheet is not acted 20 upon to an equal extent with the flues the expansion of the latter causes damage to the joint, and consequently looseness when the parts contract.

The drawing, which is a vertical central 25 section, represents a boiler embodying my improvements, the form shown being specially adapted for use with an engine, though it will be understood that the same features are applicable to all kinds of boilers, such as 30 for house use.

In the drawing, B represents the fire-pot; C, the grate, and a' the flues for the products of combustion, extending through the water-space W and connected at top and bottom to 35 the flue-sheets g and m, respectively. The water-space is continued or added to by the water-legs W', extending around the fire-pot and being formed by the shell i of said pot and the outer shell h. The water-line is 40 shown at l, and the flues a' extend above this to their points of attachment with the upper flue-sheet, and it will be apparent that these upper portions of the flues will receive the full action of the fire when it is started, which 45 action, being unmodified by the water, will cause said tubes to expand quickly and before the flue-sheet and its supporting-shell are

equally heated, with the effect above stated of causing looseness of joints. To remedy this, I employ a second set of tubes a to heat 55 the shell which supports the upper flue-sheet and through it the sheet itself, so that the expansion of these parts will be approximately equal to the expansion of the flues. The shell h', which supports the flue-sheet g, is flaring. 60 It extends below the water-line, and then horizontally to provide a supplemental flue sheet or flange K, which is connected to the outer shell h. This flange receives the supplemental flues a, which are thus shorter than 65 the main flues and below the water-line. The heating of these tubes, therefore, is modified by the water throughout. When the fire is started, the heat passes through the tubes a, as well as through the main tubes a', and the 70 heating of the shell h' is simultaneous with and about equal to that of the flues a', and the expansion is likewise equal. The steam-space S is heated from the shell as well as from the tubes, which heat acts upon 75 the flue-sheet to expand the same, and this sheet is also acted upon by the heat from the flues a. A ring 4 is placed upon the flue-flange K, which is preferably inclined inwardly and upwardly to deflect the heat 80 against the shell h', and to provide a heating-chamber x with a contracted opening at its upper end. The ring is formed with a shoulder, which receives the dome 3, provided with a damper 6, by which the entire draft may be 85 shut off. An inner dome or shell 2 is located upon the upper flue-sheet, and this includes only the main flues a'. A damper 5 in this shell serves to shut off the draft from the inner flues a' to any desired extent, leaving the 90 draft through the outer tubes entirely free. By this the burning of the fuel is under more perfect control, as the draft may be regulated and rendered even over the grate. The steam is taken from the space S through the pipe n. 95 For the purpose of rendering the draft equal at all points over the grate, and also to allow the use of a great number of tubes, the fire-pot is specially constructed, being flared at its upper part i', which brings the outer flues 100 a directly over the vertical shell of the fire-pot, so that the draft is provided from the circumference of the grate all the way across the same, the draft from the outer edge being

vertical through the flues a . This also provides a large flue-sheet relative to the diameter of the fire-pot, and more flues may thus be employed. The fire-pot is made of a single piece of metal, the upper part being flared.

5 What I claim is—

1. In combination, the fire-pot, the upper and lower flue-sheets, the main flues a' , extending from the fire-box above the water-line 10 and connected with the upper sheet g , the shell h' for the upper flue-sheet, said shell extending below the water-line, the flange K , and the series of supplemental tubes a outside the shell h' and below the water-line, substantially as described.
- 15

2. In combination, the fire-pot, the flue-sheets, the inner series of tubes a' , extending above the water-line, the shell h' and flange K , the supplemental tubes a below the water-line, and the ring 4 upon the flange K , substantially as described. 20

In testimony whereof I affix my signature in presence of two witnesses.

JOHN BARNHART.
